UNITED STATES PATENT OFFICE.

HERMAN C. PRIEBE, OF BLUE ISLAND, ILLINOIS.

DRAFT GEAR.

Application filed April 17, 1922. Serial No. 554,243.

To all whom it may concern:

Be it known that I, HERMAN C. PRIEBE, citizen of the United States, residing at Blue Island, in the county of Cook and 5 State of Illinois, have invented a certain new and useful Improvement in Draft Gears, of which the following is a full, clear, concise, and exact description.

My invention relates to car structures and 10 particularly to draft gears employed therein that contain keys as component parts thereof. In accordance with the invention, draft gear carriers are assembled with the draft sills, these carriers having openings 15 receiving the ends of the keys and applied bottom plates whereby the draft gear may be assembled with the balance of the car structure from beneath the draft sills.

The invention will be fully explained by 20 reference to the accompanying drawings showing the preferred embodiment thereof in which Fig. 1 is a plan view with parts broken away and parts shown in section, of a portion of a car structure embracing some 25 of the features of the invention; Fig. 2 is a sectional view on line 2—2 of Fig. 1, it being assumed that the center sill which is omitted in Fig. 1 is present in that figure for the purpose of the illustration contained in Fig. 30 2; Fig. 3 is a sectional view on line 3—3 of Fig. 1; Fig. 4 illustrates a portion of one of the center sills, an angle iron assembled with this sill and the body portion of one of the draft gear carriers assembled with said 35 center sill and angle irons; and Fig. 5 is a sectional view on line 5—5 of Fig. 1.

Like parts are indicated by similar characters of reference throughout the different figures.

40 The car structure shown includes two wooden center sills 1 and 2. Angle irons 5 have their upright sides secured to the center sills by means of the bolts 21 and their horizontal sides secured to the center sills by the 45 bolts 7. There are two such angle irons at each end of the car structure and the horizontal sides thereof are desirably interposed between the corresponding body bolster and the center sills.

50 A wooden end sill 9 is at each end of the car, the center sills being in abutting engagement therewith. There is also a bumper block 10 which supports a carrier 11 for supporting the coupler shank 12. This coupler shank is assembled with the coupler yoke 13. Keys 14, 15 pass through the cou-

pler yoke and beneath the wooden center sills, the ends of the keys being upon the exteriors of said sills and having exterior motion resisting springs 16 interposed therebetween. A motion resisting spring 17 is shown between the center sills and between the followers 18, 19. These followers are surrounded by the coupler yoke and the keys pass therethrough. The keys 14 and 15 are supported upon the carriers that are assembled with the center sills, preferably through the intermediation of angle irons 20, which are secured to said sills by horizontal bolts 21, and upright bolts 22 that pass through the center sills. The carriers include body portions 23 formed with openings or recesses 24 through which the keys pass. The body portions 23 of the carriers are formed with draft lug portions 25 and 26 which are engaged by the outer and inner keys 14 and 15. The carriers also include plates 27 which are held in assembly with the body portions of the carriers by means of the aforesaid bolts 22 which, with bolts 22', support the carriers. When these plates are out of place and when the carrier 11 is removed, the entire draft gear, including the coupler shank, the coupler yoke and the motion resisting mechanism assembled with these parts, may be placed in position after their complete assembly has been effected, it being merely necessary to raise the draft gear equipment to a position in which the keys will be received in the openings 24 in 90 the body portions of the carriers whereafter the plates 27 may be bolted in position.

I form the body portions of the carriers with outwardly extending depending lugs 28 and inwardly extending depending lugs 29 which are substantially in the planes of the corresponding plates 27. These lugs reinforce these plates when the draft gear is subject to pulling and pushing strains of sufficient degree to move the outer keys 14 inwardly or the inner keys 15 outwardly.

In the construction illustrated the wooden center sills are further cut away to receive the carriers and to place the keys in line with the coupler shanks. As a result, other outwardly projecting shoulders 30 are provided at the bottom of the wooden center sills which tend to weaken the same. To strengthen the sills at these shoulders I provide the body portions of the draft gear carriers with inwardly projecting extensions 31 which underlie the shoulders, the hori-

zontal sides of the angle irons 5 being preferably interposed between these extensions and the center sills. The angle irons 20, in addition to taking part in supporting the 5 draft gear carriers, also serve to strengthen the center sills at the shoulders 30 against lateral strains. The bodies of the draft gear carriers thus have abutting engagement at their inner ends with the shoulders 10 30 upon the center sills. These carrier bodies are extended outwardly sufficiently to have abutting engagement with the end sills.

The advantages of the various characteristics of a car constructed in accordance with my invention will be readily appreciated by those skilled in the art, and while I prefer to embrace all of these characteristics in the same structure, the invention is 15 not to be thus limited.

Claims relating to car construction and framing disclosed herein form the subject matter of a division of this application Serial No. 675,078, filed Nov. 16, 1923.

20 While I have herein shown and particularly described the preferred embodiment of my invention I do not wish to be limited to the precise details of construction shown as changes may readily be made without de- 30 parting from the spirit of my invention,

but having thus described my invention I claim as new and desire to secure by Letters Patent the following:—

1. In a car structure, the combination with two draft sills; of a draft gear having keys as component parts thereof; and two draft gear carriers assembled with said sills and having openings receiving the ends of said keys and including applied bottom plates whereby the draft gear may be assembled with the balance of the car structure from beneath the draft sills. 35

2. In a car structure, the combination with two draft sills; of a draft gear having keys as component parts thereof; and two draft gear carriers assembled with said sills each having a body portion and applied bottom plates between which ends of the keys are disposed, said body portion having openings therein for receiving the keys, the central part of each body portion having a depending outwardly projecting lug and a depending inwardly projecting lug substantially in the plane of the corresponding bottom plate to supplement the 40 plate in retaining the keys in position. 45

In witness whereof, I hereunto subscribe my name this fourth day of April A. D., 1922.

HERMAN C. PRIEBE.
